UNITED STATES PATENT OFFICE.

WILLIAM B. BRAGDON, OF CUMBERLAND MILLS, MAINE, ASSIGNOR TO S. D. WARREN & CO., OF BOSTON, MASSACHUSETTS.

DESIGN FOR AN ELECTRICAL TERMINAL.

SPECIFICATION forming part of Design No. 31,316, dated August 1, 1899.

Application filed November 5, 1898. Serial No. 695,623. Term of patent 7 years.

To all whom it may concern:

Be it known that I, WILLIAM B. BRAGDON, a citizen of the United States, residing at Cumberland Mills, in the county of Cumberland, State of Maine, have invented and produced a new and original Design for an Electrical Terminal, of which the following is a specification.

This design relates to electrical terminals of the class suitable for utilization as receptacles for incandescent electric lamps or for analogous uses, and has for its subject an original and beautiful configuration for such a terminal.

Figure 1 is a view in front elevation of an electrical terminal of the class indicated, in the configuration of which my novel design is embodied. Fig. 2 is a similar view in side elevation, and Fig. 3 a plan view.

The distinctive character of my design resides in or is derived from the application to

a terminal-body of laterally-extended lobes or loops merging in graceful manner into the terminal-body.

In the drawings, A designates such a terminal-body in the form of a hooded electric-lamp socket, and B lobes or loops, and the novel effect produced by their correlation is obvious and striking.

Having thus described my invention, I claim and desire to secure by Letters Patent—

The design for an electrical terminal substantially as herein shown and described.

In testimony whereof I have signed my name to this specification in the presence of two subscribing witnesses.

WILLIAM B. BRAGDON.

Witnesses:

A. S. DICKISON,
J. H. TOLMAN.
